UNITED STATES PATENT OFFICE.

HERBERT P. KELLY, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

CRANK MECHANISM FOR CUTTING MACHINES.

Application filed March 31, 1924. Serial No. 703,062.

To all whom it may concern:

Be it known that I, HERBERT P. KELLY, a citizen of the United States of America, residing at Springfield, in the county of 5 Hampden and State of Massachusetts, have invented certain new and useful Improvements in Crank Mechanism for Cutting Machines, of which the following is a specification.

10 This invention relates to operating mechanism adapted for the fabric feed of cutting machines, by means of which strips of fabric of two different widths will be cut alternately. One object of the invention is to 15 provide a mechanism of this character in which the widths of both cuts may be adjusted independently, so that different combinations of fabric widths may be had. Further objects of the invention reside in 20 its reliability of operation, in its applicability to existing machines, and in its simplicity of construction.

Referring now to the drawings,

Fig. 1 is a face view of that portion of the 25 driving mechanism embodying my invention;

Fig. 2 is a side view thereof, partly in median section;

Fig. 3 is a partial view similar to Fig. 1, 30 but with the parts in a different operative position;

Fig. 4 is a side elevation of a bias cutting machine to which my invention has been applied;

Fig. 5 is a detail side view of Fig. 1 showing the adjusting scales;

Fig. 6 is a section on line 6—6 of Fig. 2; and

Fig. 7 is a section on line 7—7 of Fig. 2. 40 Figs. 8 to 11 inclusive are diagrammatical views illustrating the operation of the device.

The bias cutting machine to which the invention is applied may be of any desired 45 type, that shown in Fig. 4 being of the type shown in the patents to Bolton 942,164, and Wegner 1,384,984, to which reference may be made for a more extended description. The feed of fabric to the cutting mechanism 50 is controlled by the oscillation of a gear segment 10 which, by means of a suitable pinion and ratchet mechanism, causes inter-

mittent rotative movement of the fabric feed roll 11. Power for causing these oscillations is transmitted to the gear segment by a link 55 12 having its lower end pivoted to a block 13 sliding in vertical ways in the machine frame. The block in turn is connected by a link 14 with the crank mechanism forming the present invention. 60

On a shaft 15 (Figs. 1, 2, and 4) rotated continuously during the operation of the machine, is fixed a crank block 16 (Fig. 2) provided with radial ways 17. A rectangular block 18 is fitted to slide in these ways, 65 and through the block is screwed a stud 19 (Fig. 6). Through both the block and the base of the stud is threaded an adjusting screw 20 extending the length of the crank and having a handle 21. An enlargement 22 70 on the screw bears against one side of a plate 23 fixed to the end of the crank (Figs. 1 and 2), and a collar 24 pinned to the screw at 25 bears on the other side of the plate. The screw is thus free to turn in the plate 75 but cannot move endwise, any turning causing a radial adjustment in the ways of the block and stud.

On the stud 19 are mounted, in longitudinal succession, a sleeve 26 and a gear 27, 80 the latter being keyed to the stud and therefore having no rotative movement with respect to crank 16. Sleeve 26 passes loosely through a hole in a long block 28 running on bearing surfaces 29 on a forked guide 30 85 terminating in an offset hub 31. The link 14 previously referred to is secured to this hub as by a thread and lock nut connection 32. The sleeve 26 preferably has a rectangular extension 33 fitting into the slot between the guides 17, as shown in Fig. 6, to hold the sleeve against rotation, and also rectangular extensions 34 which project between the crank 16 and block 28 serving as separators and also for the attachment of an index 95 plate as will be later described.

Besides carrying the stud 19 on which is mounted the gear 27, the long block 28 also carries a stud 35 pinned thereto at 36. Freely rotatable on this stud, which is 100 formed with a retaining head 37, is a second gear 38 twice the size of the first gear 27. The pivots of the two gears are by this means mounted in block 28 at a fixed dis-

tance apart so that the gears will at all times be in proper mesh. Fixed to the face of this second gear as by screws 39 are gibs 40, forming between them a slideway to receive a block 41. Screwed into this block is a stud 42 having a flange 43 at its lower end. Through this block and stud passes a threaded adjusting screw 44, secured by a flange 45 and a collar 46 to a plate 47 fastened to the ends of the gibs as was the case with screw 20. By rotating this screw the length of the crank arm formed by the span between the center of studs 35 and 42 may be varied. A sleeve 48 surrounds stud 42 having a rectangular extension 49 fitting into the gap between the gibs to prevent rotation, and side extensions 50 serving as spacers and also for the attachment of an index plate as will be described. The sleeve 48 forms a bearing upon which a link 51 pivots at one end, the other end being pivoted at 65 to the offset hub 31.

Nuts 52 and 53 on the ends of studs 19 and 42 respectively permit the two adjustable slides to be clamped in their adjusted positions, or to be loosened so that they may be adjusted by means of the threaded rods. Nut 52 bears on small gear 27 so that as it is tightened it will cause block 28 to bind in the slideway. Nut 53 bears through a collar 54 on the end of sleeve 48, and as it is tightened draws the wedge-shaped block 41 into tight wedging action with the gibs. In order to indicate the positions of adjustment of the two slides the extensions 34 and 50 respectively of the two sleeves 26 and 48 are provided with index plates 55 and 56, best shown in Fig. 5. These plates co-operate with graduations 57 and 58 respectively, secured to the side of the crank block and to the gibs 40.

The various elements going to make up the device having been thus described, it remains to consider their operation as a unitary combination. As the crank 16 rotates the small gear 27 will be carried with it. It will be followed in this travel by gear 38, which by the connecting block 28 running in the forked guide 30 is always kept at the proper meshing distance from gear 27 and yet always on one side of its center (considering the matter as referred to a fixed part of the machine). As gear 38 is free to rotate while gear 27 is not, and as the large gear is always on one side of the smaller during the latter's circular sweep at the end of the crank arm, the large gear will be rotated during each revolution of the crank a circumference on its pitch line equal to the pitch circumference of the small gear. The size of the large gear being twice the smaller, it follows that during each revolution of the crank 16 the large gear 38 will have imparted to it a half revolution.

The operation is shown diagrammatically

in Figs. 8 to 11. In these figures the positions of the several pivots are indicated by small circles, with the effective cranks and links shown in heavy lines. The crank arm formed between shaft 15 and stud 19, forming what may be termed the main crank, is indicated by 60, and the crank formed between studs 35 and 42 is indicated by 61. It is, of course, the distance between the shaft 15 and the pivot 65 in the different positions that determines the throw of the crank. Figs. 9 and 11 represent the conditions of the parts at one end of the throw on successive revolutions of the main crank. It will be observed that although stud 42 is located on opposite sides of the stud 35 the symmetrical arrangements of the parts places pivot 65 at the same distance from the main crank shaft 15 in either case. In the position of Fig. 8 the short crank 61 is extended in the same direction as the main crank, while in Fig. 10 the short crank extends in the opposite direction. The effect of this is to cause the throw of the entire crank mechanism in the position of Fig. 8 to be greater than in Fig. 10 by an amount equal to twice the radius of the small crank.

Following the mechanism through a complete cycle, the following sequence of operations occurs. Starting with the position of Fig. 9, which may be considered as the position in which segment 10 (Fig. 4) is lowered, the first half revolution of the main crank causes the stud 42 to be raised to the position of Fig. 10. This gives a throw to the link pivot 65 equal to the difference between distance b (Fig. 10) and distance a (Fig. 9). A succeeding half revolution of the main crank will retract the link pivot to position of Fig. 11, in which its distance a from the main shaft is the same as in Fig. 9. One more half revolution brings the link pivot to a point spaced a distance c from the main shaft, consequently giving to the link and to the segment 10 a throw greater than on the preceding upward movement by an amount which, as stated before, is twice the radius to which the small crank is set. The final half revolution, which completes the cycle of two revolutions of the main shaft, brings the parts again to the position of Fig. 9.

Having thus described my invention, I claim:

1. A variable throw crank mechanism comprising a crank having a radial guideway, a block adjustably mounted in the guideway, a gear secured to the block against rotation, a second gear twice as large as and meshing with the first, a second block joining the pivots of both gears, a guideway secured to the second gear, a pivot adjustably secured in the second guideway, a link having one end guided for substantially rectilinear movement and the other

end having sliding connection with the second block, and a second link connecting the first link with the adjustably mounted pivot.

- 5 2. A variable crank mechanism adapted to produce alternately different throws, comprising a crank, a crank pin fixed thereon, a

gear fixed on the crank pin, a second gear twice the size of the first and mounted so that its pivot will always remain a constant 10 distance from the pivot of the first gear but on one side thereof, and a crank pin fixed to the second gear.

HERBERT P. KELLY.
